UNITED STATES PATENT OFFICE.

EWALD KOERNER, OF DRESDEN, GERMANY, ASSIGNOR TO UNITED CIGARETTE MACHINE CO., INC., OF LYNCHBURG, VIRGINIA, A CORPORATION OF VIRGINIA.

DEVICE FOR REGULATING THE CUT OF ROD-FORMING CIGARETTE MACHINES.

Application filed November 25, 1921. Serial No. 517,778.

To all whom it may concern:

Be it known that I, EWALD KOERNER, a citizen of the Republic of Germany, and resident of Dresden, Germany, have invented certain new and useful Improvements in Devices for Regulating the Cut of Rod-Forming Cigarette Machines, of which the following is a specification.

The object of the invention is a device for regulating the cut of rod-forming cigarette machines, consisting in the provision of an oscillable ring in which is guided the actuating lever of a two-part displaceable lock co-acting with a worm drive, which lever when the ring is swung out of its middle position effects movement of this lock and effects a relative motion of the cam disc which actuates the cutting means.

The cut adjusting mechanism for rod cigarette machines are known, wherein by displacement of the carriage actuating means or by turning a wheel fixed on a counter-shaft, or by the interposition of a planetary gearing the cut may be manually adjusted corresponding to the advance or retardation of the mouth piece in consequence of the stretching or gliding of the cigarette rod. These known devices have the following disadvantages:—The displacement of the carriage actuating means provides but a very limited adjustment capability and loads the reciprocating parts, resulting in rapid wear of the driving members. The adjustment capability is also very much limited in the case where a wheel is driven on a counter-shaft, whereby inclined claws are advanced to cause the counter-shaft to rotate. The interposition of a planetary drive in which the planetary wheels may be displaced in a circle unlimited by hand has the disadvantage that the motion and power to be transmitted to the cam shaft is conducted through several wheels whereby loss of power through the interposed wheels results. In this case wear is also large and the free play, the so-called lost motion, between the driving shaft of the machine and the cutting shaft is unnecessarily large even in new machines. This lost motion causes noise and also affects accurate cutting, so that frequently cigarettes uneven in length are cut off. By the present invention these disadvantages are obviated.

The subject matter of the invention is illustrated on two sheets of drawings in two forms, by Fig. 1 in side elevation and by Fig. 4 in partial longitudinal section. Fig. 3 is a special view of the feed lock and the worm connected therewith in plan, Fig. 2 is the same along the section *a—a*. Fig. 5 is a schematic representation of the guide ring with the feed lock and the worm drive in three different positions I—III.

Revolute in the bearing block 1 is the shaft 2 upon which is fixed the cam member 3 for actuating the carriage which supports the cutting means. Loose on the shaft 2 is the hub 4 of a gear wheel 5 which is continuously driven from the machine shaft 26 by the gear wheel 27. The hub 4 carries a clamp the arms 7 and 8 of which extend in opposite directions. The arm 8 is forked to form two arms 8^a and 8^b which serve as a bearing for the shaft 6^a upon which is fixed a worm 6 and a locking wheel 10. The arm 7 mounted on the hub 4 carries a counter-weight 20 to obtain motion without shock. The worm 6 engages a worm wheel 9 fixed on the shaft 2. Engaging into the teeth of the locking wheel 10 are oppositely arranged pawls 11^a and 11^b under the action of springs 13, which pawls are revolute about studs 14. The studs are mounted on a double armed lever 12 which is oscillable on the shaft 6^a of the locking wheel 10. In the middle of the double armed lever 12 is an arm 15 at the free end of which there is revolutely mounted a ball-like roller 16. The roller 16 is guided in an upright ring 17 which is oscillable about a stud 21 carried in the bearing blocks 22. The guide ring 17 surrounds the worm 6, the worm wheel 9 and the counter-weight 20 and is provided above with a handle 23. Consequently the ring may be swung manually from its middle position laterally to the right or to the left. In its middle position the ring is held by pressure springs 24 which act upwardly against the arms of a double lever 25 provided on the ring. Stops 26^a provided on the arms of the double lever 25 prevent the ring from being swung out too far laterally. The operation of the device is as follows: By means of the gear wheel 27 mounted on the machine shaft 26, the gear wheel 5 which is loose on the shaft 2 is continuously

rotated. The gear wheel 5 entrains the arms 8^a and 8^b connected with its hub, also the worm 6 which bears between these arms and the worm wheel 9 which engages with the 5 worm 6, without however the worm being rotated about its axis. Furthermore the gear wheel 5 entrains the arm 7 which is connected with its hub 4 and which serves as a carrier for the counter-weight 20. Inasmuch as the worm wheel 9 is fixed on the shaft 2 the latter is also rotated. This rotation is imparted to the cam member 3 which is fixed on the shaft 2 and which cam member serves for the actuation of the carriage supporting the cutting means.

If the cutting means are to be adjusted, then the guide ring 17 is moved by actuation of the handle 23 so far to the right or to the left until this movement is limited by one of 20 the stops 26^a. The roller 16 running in the guide ring is deflected in the upper part of its course in the ring to the right or to the left from its middle position by reason of the inclination of the ring to the extent that 25 the ring is laterally oscillated (positions I and III, Fig. 5). In the lower part of its course however, the roller 16, following the guide path of the ring, always returns to the middle position (Fig. 5, position 2) so that by the coursing of the roller 16 in the inclined ring 17 the double lever 12 connected therewith is swung about its axis and always to that side to which the ring 17 was oscillated. By this movement of the double 30 lever 12 in the inclined position of the same one or the other of the pawls 11^a and 11^b attached thereto is actuated and locking wheel 10 is advanced by one of the pawls to the right or to the left dependent upon whether 35 the guide ring was oscillated to the right or to the left, while the opposite pawl is raised by a nose 18 provided on a fixed bearing arm 8. The resulting rotation of the ratchet wheel 10 is imparted to the worm 6 fixed to 40 the shaft of such wheel 10, and the rotation of this worm effects rotation of the worm wheel 9 fixed to the shaft 2. Inasmuch as the cam member 3 is fixed to the shaft 2 rotation of such cam member 3 also results in 45 relation to sleeve 4, in a direction which depends on the direction of oscillation of the ring 17. It is thus possible to impart to the rotary motion of the cam member 3, which actuates the carriage of the cutting knives, an advance motion or a retardation dependent on whether the ring 17 is swung to the right or to the left. By virtue of the fact 50 that the inclination of the ring 17 is limited by the stops 26^a an excessively rapid displacement of the cam member 3 and of the cutting means is not possible, although this is possible with the devices of the prior art which leads to the production of defective cigarettes. Upon releasing the handle 23 of 55 the guide ring 17 the latter snaps under the

influence of the pressure springs 24 into its middle position and the displacement of the cam member 3 ceases.

I claim:

1. In mechanism of the class described, a 70 rotary actuating member, a rotary driving member therefor, the actuating and driving members being angularly movable in relation to each other, gearing arranged to rotate with said members and connecting them together and operable to vary the angular relation of the members, said gearing having an operating member and a manually operated controlling member, said controlling member being adjustable and co-operating with said operating member to cause said gearing to vary the relative angular position of the actuating member and driving member.

2. In mechanism of the class described, a 85 rotary actuating member for the cut-off mechanism of cigarette machines, a rotary driving member therefor, the actuating and driving members being angularly movable in relation to each other, gearing arranged to rotate with said members and connecting them together and operable to relatively rotate the members, said gearing having an operating member, and a manually operated 90 non-rotating controlling member, said controlling member cooperating with said gearing-operating member and being adjustable to different planes intersecting the axis of rotation of said actuating and driving members to cause said gearing to vary the relative angular positions thereof.

3. In mechanism of the class described, a 105 rotary actuating member for the cut-off mechanism of cigarette machines and a driving member therefor arranged to rotate on a common axis, gearing connecting said members and serving to connect and adjust them angularly in relation to each other and also rotating with said members, ratchet mechanism for driving said gearing and having a projecting operating member arranged to oscillate approximately in a plane containing the axis of rotation of said members, and a controlling ring engaged by said operating member in its rotative movement, said ring being manually adjustable in different planes to cause oscillation of said operating member during its rotation to move said actuating member rotatively in relation to its driving member.

4. In mechanism of the class described, a 115 rotary actuating member for the cut-off mechanism of cigarette machines and a driving member therefor arranged to rotate on a common axis, gearing connecting said members and serving to connect and adjust them angularly in relation to each other and also rotating with said members, a two-way ratchet mechanism for driving said gearing in either of two directions and having an 120

operating member projecting radially and arranged to oscillate in a plane of said axis of rotation, and a controlling ring engaged by said operating member throughout its 5 rotative movement, said ring being manually adjustable in different planes to cause oscillation of said operating member during its rotation to advance or retard said actuating member in relation to its driving 10 member.

5. In mechanism of the class described, a shaft, an actuating member secured thereon, a driving member rotatably mounted on the shaft, a worm and worm gear connecting 15 said driving member and shaft, ratchet mechanism arranged to oscillate in a plane of the shaft axis and to drive the worm to adjust said actuating member angularly in relation to the driving member, an operating 20 arm extending from said ratchet mechanism and normally moving in a plane perpendicular to the shaft axis, and a controlling annulus engaging said arm and pivoted at one side of the shaft axis and movable on 25 its pivot to cause said arm to reciprocate during its rotation and vary the angular relation of said actuating member and its driving member.

6. In mechanism of the class described, a 30 shaft, an actuating member secured thereon, a driving member rotatably mounted on the shaft, a worm and worm gear connecting said driving member and shaft, two-way ratchet mechanism arranged to oscillate in 35 a plane of the shaft axis and to drive the worm one way or the other to adjust said actuating member angularly in relation to the driving member, an operating arm extending radially from said ratchet mechanism 40 and normally moving in a plane perpendicular to the shaft axis, and a controlling annulus engaging said arm throughout its rotative movement and pivoted in said plane at one side of the shaft axis and movable on its pivot to cause said arm to reciprocate 45 during its rotation and vary the angular

relation of said actuating member and its driving member in either direction.

7. In mechanism of the class described, a 50 shaft, an actuating cam body secured thereon, a sleeve rotatably mounted on the shaft, means for driving the sleeve constantly, a worm gear on said shaft, a worm rotatably mounted on said sleeve and engaging the worm gear, ratchet mechanism for driving the worm, an operating arm extending from the ratchet mechanism and normally revolving in a plane perpendicular to the shaft axis, and a controlling ring surrounding the 55 shaft and having a track for said arm, said ring being pivoted in the plane last mentioned at one side of the shaft and adjustable about its pivot in oblique planes at either side of said perpendicular plane to cause oscillation of said operating arm to move 60 said actuating member angularly in relation to the driving sleeve in accordance with the positioning of said controlling ring.

8. In mechanism of the class described, a 65 shaft, an actuating cam body secured thereon, a sleeve rotatably mounted on the shaft, means for driving the sleeve constantly, a worm gear on said shaft, a worm rotatably mounted on said sleeve and engaging the worm gear, oscillatable ratchet mechanism 70 for driving the worm in either rotative direction, an operating arm extending from the ratchet mechanism and normally revolving in a plane perpendicular to the shaft axis, and a controlling ring surrounding the 75 shaft and having a track for said arm, said ring being pivoted in the plane last mentioned at one side of the shaft and adjustable about its pivot in oblique planes at either side of said perpendicular plane to cause 80 oscillation of said operating arm to advance or retract said actuating member rotarily in relation to the driving sleeve in accordance with the positioning of said controlling ring.

Signed at Dresden, Germany, this 28th 85 day of October, A. D. 1921.

EWALD KOERNER.
